(57) CLAIM

The ornamental design for a vehicle sports bar, as shown and described.

DESCRIPTION

FIG. 1 is a rear perspective view of the vehicle sports bar of the present invention showing my new design with the broken lines depicting solely environmental structure and forming no part of the claimed design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a second embodiment of the vehicle sports bar of the present invention showing my new design with the broken lines depicting solely environmental structure and forming no part of the claimed design;

FIG. 9 is a top plan view thereof;

FIG. 10 is a front elevational view thereof;

FIG. 11 is a left side elevational view thereof;

FIG. 12 is a right side elevational view thereof;

FIG. 13 is a bottom plan view thereof; and,

FIG. 14 is a rear elevational view thereof.

The vehicle sports bar is shown on an enlarged scale in FIGS. 2-7 and FIGS. 9-14.
